REFRIGERATION APPARATUS

Robert H. Tull and Elo C. Tanner, Springfield, Mass., assignors to Westinghouse Electric & Manufacturing Company, East Pittsburgh, Pa., a corporation of Pennsylvania

Application November 10, 1934, Serial No. 752,402

6 Claims. (Cl. 62—115)

Our invention relates to refrigeration apparatus, particularly to the construction of the evaporator and its associated elements.

It is an object of our invention to provide an improved evaporator construction and to connect the evaporator with its associated elements to secure improved performance and efficiency.

This and other objects are effected by our invention, as will be apparent from the following description and claims taken in connection with the accompanying drawing, forming a part of this application, in which:

Fig. 1 is a sectional view, of a beverage cooling refrigerator constructed in accordance with the invention;

Fig. 2 is a plan view, partly in section, of the cooling element shown in Fig. 1; and

Fig. 3 is an enlarged sectional view of a portion of the cooling element.

Referring specifically to the drawing for a detailed description of the invention, numeral 1 designates a refrigerator cabinet in this instance for wet cooling and storage of bottled beverages. The cabinet 1 is divided into an apparatus compartment 2 and a cooling compartment 3, preferably suitable for containing a body of liquid, such as water. A movable closure 4 is provided for obtaining access to the cooling compartment 3.

A hermetically sealed refrigerating unit is associated with the cabinet 1 and comprises, generally, a cooling element 5, a hermetically sealed motor-compressor set 6, a condenser 7, a fan 8 and a sealed float-operated valve mechanism 9 in a container 11. The cooling element 5 is disposed in the cooling compartment 3, while the rest of the apparatus is disposed, preferably, in the apparatus compartment 2.

In operation, refrigerant vapor is withdrawn from the cooling element 5 through a conduit 12 by the suction of the motor-compressor unit 6 and, after being compressed, is conveyed to condenser 7 through a conduit 13, where the compressed vapor is liquefied. Liquid refrigerant is supplied to the cooling element 5 through a conduit 14 from the float operated valve 9 in response to the level of liquid refrigerant in the container 11, the refrigerant being conveyed to the container 11 from condenser 7 through a conduit 15. The conduits 12 and 14 are preferably flexible and extend from the apparatus compartment 2, up the side of the cabinet and through an opening 16 in the top of the cooling compartment 3 to connect with the cooling element 5. It is readily seen that the refrigerating mechanism may be completely assembled and sealed,

and then removed or replaced in the cabinet without breaking the conduit connections.

In some applications, as heretofore stated, it is desirable to utilize a continuous or once-through coil type cooling element, because it is flexible as to size and shape and requires less refrigerant charge than the conventional flooded evaporator of the same capacity. The cooling element 5 comprises a continuous coil of conduit 17, connected at both ends with a surge chamber 18 to prevent surges of liquid from entering outlet conduit 12. The refrigerant inlet conduit 14 extends through the surge chamber 18 into the inlet end 19 of the cooling element conduit 17. A plug 21 prevents liquid refrigerant from entering the surge chamber 18 before it has traversed the conduit 17. The outlet 22 of the cooling element conduit discharges vapor into the surge chamber 18, from which the vapor is withdrawn through outlet conduit 12 which also connects with the surge chamber 18.

The inlet conduit 14 is of small diameter, while the outlet conduit 12 is of larger diameter and encloses the inlet conduit 14. By making the diameter of the inlet conduit small, the refrigerant does not expand appreciably until it reaches the cooling element 5. By disposing the inlet conduit 14 within the outlet conduit 12 in heat exchange relation with the cold refrigerant vapor therein, expansion in the inlet conduit 14 is further inhibited. The efficiency of the entire system is, therefore, increased, because practically all the expansion of liquid refrigerant occurs in the cooling element 5. Furthermore, the heat exchanger for cooling the inlet liquid improves the efficiency of the system. In addition, condensation of moisture from the atmosphere, resulting in dripping of the inlet conduit 14, is prevented by the novel construction and arrangement of the inlet and outlet conduits which raises the dew point of those portions of the conduits exposed to the atmosphere outside the cooling compartment.

From the foregoing, it will be apparent that we have provided a hermetically sealed refrigerating system which is efficient and which is easily removed and replaced in a refrigerator cabinet. Furthermore, we have reduced or prevented dripping from the outside conduit connections of the system, even though the distributing device for liquid refrigerant is disposed a considerable distance from the cooling element.

We do not wish to be limited to a float operated valve in the system unless specifically set forth in the claims since other forms of distrib-

uting devices may be utilized in practicing some parts of our invention. Furthermore, we do not wish to be limited to compression types of refrigeration apparatus unless specifically set forth in the claims, since other types of refrigerating apparatus may be utilized in practicing our invention.

While we have shown our invention in but one form, it will be obvious to those skilled in the art that it is not so limited, but is susceptible of various changes and modifications without departing from the spirit thereof, and we desire, therefore, that only such limitations shall be placed thereupon as are imposed by the prior art or as are specifically set forth in the appended claims.

What we claim is:

1. In a refrigerating system, the combination of a compartment to be cooled, a cooling element 20 in said compartment having a refrigerant inlet and outlet, a compressor having a refrigerant inlet and outlet, a condenser having a refrigerant inlet and outlet, a conduit connecting the outlet of the cooling element with the inlet of the 25 compressor, a second conduit for conveying liquid refrigerant from the outlet of the condenser to the inlet of the cooling element, and means located in said second conduit for controlling the flow of liquid refrigerant to the cooling element, 30 the portion of said second conduit between said controlling means and said cooling element being of reduced flow area to retard the expansion of liquid refrigerant before reaching the cooling element and being located in heat exchanging 35 relation with the said first conduit connecting the outlet of the cooling element with the inlet of the compressor, said flow control means and portions of both of said conduits being disposed outside of said compartment to be cooled.
2. In refrigeration apparatus, the combination of a cooling element, means for removing refrigerant vapor from said cooling element and for liquefying said vapor, a flow control valve for controlling the admission of refrigerant to said 40 cooling element and for substantially preventing back flow of refrigerant from said cooling element, a flow restricting conduit connecting said flow control valve and the cooling element to retard the expansion of liquid refrigerant before 45 reaching said cooling element, and an outlet conduit connecting said cooling element and said first means, said flow restricting conduit and said outlet conduit being arranged in heat exchange 50 relation with each other.
3. In refrigeration apparatus, the combination of a cooling element, means for removing refrigerant vapor from said cooling element and for liquefying said vapor, a float-operated means for controlling the flow of liquid refrigerant from

said first means to the cooling element, a flow restricting conduit connecting the float-operated means and the cooling element to maintain liquid refrigerant in said flow restricting conduit, and an outlet conduit connecting said cooling element and said first means, said flow restricting conduit and outlet conduit being arranged in heat exchange relation with each other.

4. In refrigeration apparatus, the combination of a cooling element, means for removing refrigerant vapor from said cooling element and for liquefying said vapor, an outlet conduit connecting said cooling element and said means, an inlet conduit from said means to said cooling element and float-operated means in said inlet conduit for controlling the flow of refrigerant from said means to said cooling element, the portion of said inlet conduit between said float-operated means and said cooling element being of reduced flow area and substantial length to retard expansion of the liquid refrigerant before reaching the cooling element and being disposed in heat exchange relation with said outlet conduit.

5. In refrigeration apparatus, the combination of a cooling element, a compressor, a condenser, an outlet conduit from said cooling element connecting with said compressor for conveying cold refrigerant vapor to the compressor, a float-operated valve for controlling the flow of liquid refrigerant from said condenser to said cooling element, and a flow restricting conduit connecting said float-operated valve and said cooling element, said flow restricting conduit being of sufficient restriction to maintain liquid therein at a higher temperature than the refrigerant in said outlet conduit, said flow restricting conduit and said outlet conduit being disposed in heat exchange relation, whereby the liquid in the flow restricting conduit is cooled by the refrigerant vapor in the outlet conduit.

6. In a refrigerating system, the combination of a once through continuous evaporator coil, a compressor, a condenser, a surge chamber located at and communicating with the outlet end of the evaporating coil, a conduit connecting the surge chamber with the inlet of the compressor, a conduit for conveying liquid refrigerant from the condenser to the inlet end of the evaporator coil, said last-mentioned conduit extending through the surge chamber and into the inlet end of the evaporator coil, means for preventing refrigerant from entering the surge chamber until it has passed completely through the evaporator coil and means located in said conduit for controlling the flow of liquid refrigerant to the evaporator coil.
